UNITED STATES PATENT OFFICE

CASPER F. HANSON, OF ALBERT LEA, MINNESOTA, ASSIGNOR TO OLSON MANUFACTURING COMPANY, OF ALBERT LEA, MINNESOTA, A CORPORATION OF MINNESOTA

STANCHION

Application filed March 8, 1928. Serial No. 260,011.

My present invention has for its object to provide an extremely simple and highly efficient stanchion for barn equipment that is very strong, rigid and durable, that cannot be accidentally released and that is easy to operate and of comparatively small cost to manufacture.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a fragmentary perspective view of a stall structure equipped with the improved stanchion;

Fig. 2 is a top view of the stanchion, on an enlarged scale, removed from the stall;

Fig. 3 is a fragmentary side elevation of the same with some parts shown in vertical section and other parts shown in different positions by means of broken lines;

Fig. 4 is a bottom view of the stanchion;

Fig. 5 is a detail view in section taken on the line 5—5 of Fig. 3; and

Fig. 6 is an edge elevation showing the hinge fitting connecting the secondary side member of the stanchion to the bottom member thereof.

The numeral 7 indicates a stall structure, as an entirety, with the exception of the top bar 8 and the partition 9 between the manger and stall. The improved stanchion is of the floating type and is held suspended over the partition 9 by a short chain 10 anchored to the top bar 8. A short chain 11 attached to the bottom member of the stanchion and anchored to the partition 9 limits the swinging movement of said stanchion.

The stanchion, as shown, comprises main and secondary side members 12 and 13, respectively, in parallel arrangement and top and bottom members 14 and 15, respectively, which extend perpendicular to said side members. All of the members of the stanchion 12, 13, 14 and 15 are formed from U-bars, the rounded backs of which form the inner edge portions of the stanchion and the

flanges thereof are turned outward in the plane of the stanchion. The top and bottom members 14 and 15 are integral with the main side member 12 and are formed by bending the end portions of said side member at right angles thereto.

A hinge fitting 16 connects the secondary side member 13 to the bottom member 15 for outward swinging movement from a closed position, as shown by full lines in Fig. 3, to an open position, as indicated by broken lines in said figure. This hinge fitting 16 is U-shaped in cross section with the lower end portion of the secondary side member 13 and the free end portion of the bottom member 15 extending between the flanges thereof and having a relatively tight fit therewith. The flanges of the hinge fitting 16 are relatively wide and completely overlap the flanges of the secondary side member 13 and bottom member 15.

The back of the hinge fitting 16 extends obliquely between the secondary side member 13 and the bottom member 15 and affords a brace, the upper end of which engages the back of said secondary side member and the lower end of which engages the back of the bottom member 15 when said secondary side member is closed, as best shown by full lines in Fig. 3. A pair of rivets 17 inserted through aligned bores in the overlapping flanges of the secondary side member 13 and hinge fitting 16 rigidly connect said side member and hinge fitting. A hinge bolt 18 is inserted through aligned bores in the flanges of the bottom member 15 and hinge fitting 16 near the lower or rear end of the back of said fitting and connects the same to the bottom member 15 for hinge-acting movements to permit opening and closing movements of the secondary side bar 13.

It will be noted by reference to Fig. 3 that the bottom member 15 is provided with a plurality of longitudinally spaced bores 19 through any one pair of which the pivot bolt 18 may be inserted to adjustably connect the hinge fitting 16 to said bottom member to position the secondary side member 13 different distances from the main side member 12 to vary the width of the stan-

chion. It will also be noted by reference to Fig. 3 that the pivot bolt 18 extends through the upper link of the chain 11 at a point between the flanges of said bottom member and connects said chain to the stanchion.

5 The flanges of the hinge fitting 16 have long contact with the outer faces of the flanges of the bottom member 15 at all times and in all positions of the secondary side member 13 and thereby securely hold the same against lateral or angular twisting movements. The lower end of the secondary side member 13 is spaced above the back of the bottom member 15 to permit the required pivotal movement of the hinge fitting 16 during the opening and closing of the secondary side member 13 and the outer lower corners of the flanges of the secondary side member 13 engage the back of the bottom member 15 as a positive stop to limit the opening movement of said secondary side member.

Nested with the free end portion of the top bar 14 is a U-shaped fitting 20 that is rigidly but detachably secured thereto by inner and outer nut-equipped bolts 21 passed through aligned bores in the flanges of said member and fitting. By reference to Fig. 3 it will be noted that there is a plurality of longitudinally spaced bores 22 in the flanges of the top member 14 for the bolts 21 to permit longitudinal adjustment of said fitting on the top member 14. These bores 22 are so arranged in respect to the bores 19 that the secondary side bar 13 is always kept in parallel arrangement with the main side bar 12 during the adjustment of the hinge fitting 16 and the fitting 20 on the bottom member 15 and top member 14, respectively.

40 The outer end of the back of the fitting 20 is shaped to fit around the back of the secondary side member 13 as a stop 23 for the secondary side member 13, when closed. The flanges of the fitting 20 are extended outward of the stop 23 to afford a pair of diverging guide prongs 24 for directing the secondary side member 14 to its seat 23 and for holding said side member against lateral movement in respect to the top member 14. 45 A latch in the form of a hook 25 is mounted between the flanges of the top member 14 and its shank is pivotally connected thereto by the inner bolt 21 for vertical swinging movement. This latch 25 is gravity held in an operative position in which it overlies the upper end of the secondary side member 13 and engages the back thereof between its flanges to hold said side member closed against the stop 23. The width of the latch 50 25 is such as to snugly fit between the flanges of the top member 14 and is held thereby against lateral movement, as best shown in Figs. 2 and 3.

On the outer end of the latch 25 is a cam 55 surface 26 arranged to be engaged by the

back of the secondary side member 13 during its closing movement and lift said latch out of its path of movement and then allow said latch to drop by gravity after having passed the same into interlocking engagement with the back of said secondary side member.

70 The chain 10 is attached to the stanchion by having its lower link inserted between the prongs of the bifurcated pivoted end of the latch 25 with the inner bolt 21 extending therethrough, as best shown in Figs. 2 and 3. It will also be noted that the latch 25 at its crotch has oblique engagement with the lower link of the chain 10 and holds the same in crank-acting arrangement therewith so that the weight of the stanchion on the said link holds the latch 25 closed so that the same cannot be accidentally released. Obviously, the fitting 20 and latch 25 rigidly connect the secondary side member 13 and top member 14 when said secondary side member is closed.

75 One of the primary objects of pivoting the hinge fitting 16 at its lower or inner corner to the bottom member 15 with its side flanges overlapping the sides of said bottom member is to securely hold the secondary side member 15 for straight-line swinging movement and against lateral angular movement from said bottom member so that the upper or free end of the secondary side member will be directed between the guide prongs 24 during its closing movement for interlocking engagement with the latch 25. It will thus be seen that the operator in closing the secondary side member 13 simply swings the same inward without giving any thought as to directing the same to the latch 25 with which said side member automatically interlocks at the completion of its closing movement.

100 What I claim is:

1. A stanchion comprising main and secondary side members, top and bottom members, a latch in the top member for the secondary side member, and a hinge fitting connecting the secondary side member to the bottom member for outward swinging movement from a closed position in the plane of the stanchion, said hinge fitting having guide flanges that engage the bottom member and direct the secondary side member to the latch during its closing movement.

105 2. A stanchion comprising main and secondary side members and top and bottom members, said bottom member extending under the lower end of the secondary side member and spaced therefrom, a hinge fitting connecting the secondary side member to the bottom member for outward swinging movement in the plane of the stanchion, said hinge fitting comprising a pair of laterally spaced side flanges rigidly secured to the secondary side member, extending therebelow with the bottom member extending longitudinally

therebetween, said side flanges being materially wider than the secondary side member, pivoted to the bottom member between the main and secondary side members and offset materially toward the main side member from the secondary side member, whereby endwise movement is imparted to the secondary side member during its opening and closing movements, said side flanges extending from their pivotal connection with the bottom member to substantially the outer face of the secondary side member and having long bearing contact with the sides of said bottom member longitudinally there-
5 of to securely hold said secondary side member against lateral or angular movements transversely of the plane of the stanchion and with the upper end of the secondary side member in alignment with the top member,
10 and a latch for securing the secondary side member to the top member.
15

3. The structure defined in claim 2 in which the lower end of the secondary side member is arranged to engage the underlying bottom member as a stop to limit its opening movement.

4. The structure defined in claim 2 in which the hinge fitting is in the form of a right-angled triangle with its right-angled sides at the outer faces of the secondary side member and the bottom member and with its hypotenuse between the secondary side member and bottom member.

5. The structure defined in claim 2 in which the hinge fitting is U-shape in cross-section and in the form of a right-angled triangle with its right-angled sides substantially at the outer faces of the secondary side member and the bottom member and with its hypotenuse, which is a transverse portion of the hinge fitting, extending between the secondary side member and the bottom member.

6. The structure defined in claim 2 in which the hinge fitting is U-shape in cross-section and in the form of a right-angled triangle with its right-angled sides substantially at the outer faces of the secondary side member and the bottom member, and with its hypotenuse, which is a transverse portion of the hinge fitting, extending between the secondary side member and the bottom member, and in which one end of the transverse portion of the hinge fitting engages the inner face of the secondary side member and in which the other end thereof engages the bottom member when the secondary side member is closed.

7. The structure defined in claim 2 in which the hinge fitting is U-shape in cross-section and in the form of a right-angled triangle with its right-angled sides substantially at the outer faces of the secondary side member and the bottom member, and with its hy-
60 pothenuse, which is a transverse portion of

the hinge fitting, extending between the secondary side member and the bottom member, and in which one end of the transverse portion of the hinge fitting engages the inner face of the secondary side member and in which the other end thereof engages the bottom member when the secondary side member is closed, said U-shape hinge fitting affording a fillet for the respective corner of the stanchion and completely closes the joint between the secondary side member and the bottom member from the inside of the stanchion and the two sides thereof in all positions of the secondary side member.
70
75

8. A floating stanchion comprising main and secondary side members and top and bottom members, said secondary member being hinged to the bottom member for outward swinging movement from a closed position in the plane of the stanchion, said top member and secondary side member being U-shaped in cross section with the side flanges thereof extending outward, a fitting in the form of a short U-bar fitted around the top member for endwise sliding movement thereon and extending outward thereof, the sides of the outer end portion of the fitting being outwardly extended in diverging relation to afford a pair of guides for the secondary side member during its closing movement and for holding the same against lateral movement, the outer end of the transverse portion of the fitting affording a stop which limits the closing movement of the secondary side member, said top member having in its sides a plurality of longitudinally spaced pairs of holes, a bolt extending through aligned holes in the sides of the fitting and the holes of any one of said pairs to rigidly secure the fitting to the top member in different longitudinal adjustment, a hanger for the stanchion including a ring between the sides of the fitting and through which the bolt extends, and a gravity-closed latch pivoted to the bolt and engaging the transverse portion of the secondary side member as a cooperating latch member to hold said side member closed.
